UNITED STATES PATENT OFFICE.

WILLIAM H. COLLIER, OF BRENTWOOD, TENNESSEE.

DOOR-LATCH.

1,221,685.

Specification of Letters Patent.

Patented Apr. 3, 1917.

Application filed July 20, 1916. Serial No. 110,303.

To all whom it may concern:

Be it known that I, WILLIAM H. COLLIER, a citizen of the United States of America, and a resident of Brentwood, county of 5 Davidson, and State of Tennessee, have invented a certain new and useful Door-Latch, of which the following is a specification.

My invention relates generally to door latches, and particularly to latches for carriage and automobile doors. It is very necessary that such latches shall act positively and with certainty; and it is also desired that the construction of such latches 15 shall be such that their mechanism shall be entirely concealed, except for the operating handle and for the portion of the bolt which protrudes from the door when the latter is open. It is further desirable that such 20 latches shall be extremely simple and relatively inexpensive. The improved latch herein described possesses the above qualities and further comprises a novel spring construction whereby the latch is much simplified.

The object of my invention is to provide a latch adaptable particularly for the purposes specified and which shall be simple, positive in action, compact, and readily concealed.

I will now proceed to describe my invention with reference to the accompanying drawing, and will then point out the novel features in claims. In said drawing:

35 Figure 1 shows a perspective elevation of my improved latch applied to an automobile door, which latter, and the adjacent portion of the frame of the car body, are shown in dotted lines.

40 Fig. 2 shows on a larger scale, a central vertical section of a portion of the door frame and of the bolt-socket, the bolt itself and its operating spring lever being shown in elevation.

45 Fig. 3 is an end view of the parts shown in Fig. 2.

Fig. 4 is a view similar to Fig. 2, but showing an alternative construction.

50 Fig. 5 is an end view of the parts shown in Fig. 4.

Fig. 6 shows a transverse section of a portion of the lever 7 of Figs. 2 and 3.

Fig. 7 is a view similar to Fig. 2 and

Fig. 8 is a view similar to Fig. 3, of an alternative construction. 55

Fig. 9 is a view similar to Fig. 2, and

Fig. 10 a horizontal section, of a further alternative construction.

Referring first to Figs. 1, 2 and 3, numeral 1 designates the frame of the door and 60 numeral 2 the frame of the adjacent portion of the car body. 3 designates a tubular socket fitted into the frame of the door and having at one end a flange 4 recessed into the edge of the door frame, while at its 65 other end this tubular socket has a holding nut 5. Within the socket 3 is the latch bolt 6, which may have any suitable cross section, but in the particular construction shown is cylindrical. The outer end of this 70 bolt 6 is beveled, as is customary.

7 designates an operating lever for the latch, secured to the bolt 6 by a pin 8 working in a corresponding slot of the bolt; and this latch lever 7 has as an integral part of 75 it a U-shaped spring 7^a. The lever 7 is of spring steel and is a bar of rectangular cross section which, below the bolt 6, is twisted at right angles and then bent into a U, the shorter leg of the U being curved 80 around to form an eye for the passage of the socket 3; the nut 5 holding this shorter leg of the U tightly against the door frame, and the end 7' of this shorter leg being turned up as indicated particularly in Fig. 85 6, so that this shorter leg of the U acts as a spring lock washer to hold the nut 5.

As shown particularly in Fig. 3, but also in Fig. 1, the lever 7 is seated within a slot in the rearwardly projecting portion of the 90 bolt 6.

The set of the spring 7^a is such that it tends to press the bolt 6 outward or to the left of Fig. 2. The lever 7 is provided with a handle 9 whereby the bolt 6 may be retracted against the action of the spring 7^a; 95 this handle 9 working through a slot in a guide plate 10.

In the frame of the car, and opposite the tubular bolt socket 3, there is another simi- 100

lar socket 11 which receives the protruding front end of the bolt when the door is closed and the handle 9 released so as to permit the bolt to be held forward by the spring 7^a.

5 It will be seen that the lever 7 and its spring 7^a are located entirely within the upholstery space of the door and so are concealed; that the sockets 7 and 11 are also concealed, except at their front ends, so that 10 in practice the only visible portions of the latch are the front ends of these sockets, the front of the bolt, the handle 9, and the guide plate 10.

Figs. 4 and 5 show several alternatives to 15 the constructions shown in Figs. 2 and 3. For example, the bolt socket, here designated by numeral 3^a, is screw threaded exteriorly, and is screwed into the door frame 1, instead of being held therein by a flange and 20 lock nut; and while this bolt socket 3^a may have a lock nut 5 (indicated in Fig. 4 in dotted lines) this lock nut will in general be omitted. In the construction shown in Fig. 4 the bolt spring is not integral with 25 the operating lever, there designated by numeral 7^b, but is an ordinary helical spring, located within the bolt socket 3^a and bearing against the bolt 6^a, which latter is of reduced diameter, where the spring 7^c surrounds it; this spring also bearing against a flange 3^b of the bolt socket. The operating lever 7^b is anchored at its lower end by 30 means of a headed screw 7^d, the lower end 7^e of this operating lever being rounded so as 35 to present a rounded fulcrum surface to the face of the door frame 1, against which it is held by the head of the screw 7^d. The operation of this mechanism is the same as 40 that of the mechanism shown in Figs. 2 and 3.

It is often desired that the lock bolt may retreat and then advance again without movement of the operating lever. For example, 45 when the door is closed without use of the operating handle 9 (as, for example, when the door is "slammed" shut) it is desirable that the projecting operating handle 9 shall not move. Figs. 7-10 inclusive illustrate 50 constructions otherwise similar to those of Figs. 1-5 inclusive, wherein this result is obtained. In the construction shown in Figs. 7 and 8 (otherwise generally similar to the constructions shown in Figs. 4 and 5) the pin 8 is at the rear of the lever 7^b and 55 therefore obviously the bolt 6^a may retreat and again advance without affecting the position of the lever 7^b (and its handle 9—see Fig. 1).

In the construction shown in Figs. 9 and 60 10, the tubular socket 3^c (corresponding to the tubular socket 3 of Figs. 2 and 3) is extended rearwardly of the operating lever 7^b and is slotted, rearwardly of said lever, the lever playing in such slot, 12. The lock

bolt, 6^b, also has in it a slot, 13, in which the 65 lever 7^b is also adapted to play, and across said bolt and its slot 13, and in rear of the lever 17, is located a pin 8^a. Behind the bolt 6^b there is a spring 7^c, abutting at its rear end against the pin 14. 70

It will be clear that in this construction, as in the construction shown in Figs. 7 and 8, the bolt 6^b may retract and thereafter advance without movement of the lever 7^b.

What I claim is:—

1. A latch such as described comprising a bolt-socket, a bolt slidably mounted therein, and an operating bar of rectangular section fitting within a slot in the rear end of said bolt and connected to said bolt, and, 80 below the point of such connection, twisted into a plane at right angles to its plane where connected to such bolt, the so twisted portion of the lever being provided with means for holding it in place, the structure 85 comprising spring means tending to project the bolt.

2. A latch such as described comprising in combination a bolt socket, a bolt slidably mounted therein, and an operating lever for 90 said bolt consisting of a U-spring, one arm of which is extended to form the operating lever, the other arm of such spring adapted to be secured to a fixed support, the extended arm of said spring being connected to the 95 bolt and adapted to actuate it.

3. A latch such as described comprising in combination a bolt socket, a bolt slidably mounted therein and having a rearwardly projecting slotted portion, and an operating 100 lever for said bolt consisting of a bar of rectangular section fitting within the said slot in the rear end of said bolt and connected to said bolt, and below the point of such connection, twisted into a plane at 105 right angles to its plane where connected to such bolt, and thereafter bent into a U-spring, and means for anchoring the said spring.

4. A latch such as described comprising 110 in combination a bolt socket, a bolt slidably mounted therein and having a rearwardly projecting slotted portion, and an operating lever for said bolt consisting of a bar of 115 rectangular section fitting within the said slot in the rear end of said bolt and connected to said bolt, and below the point of such connection, twisted into a plane at right angles to its plane where connected to such bolt, and thereafter bent into a U- 120 spring, said spring having an aperture through which said bolt socket passes, and said bolt socket having means for anchoring the spring.

5. A latch such as described comprising 125 in combination a bolt socket, a bolt slidably mounted therein, an operating lever, means carried by the bolt engaging the rear of said

operating lever, and spring means tending to press said bolt forward; the construction being such that because of the engagement of the bolt with the rear of the operating lever, the bolt may retreat and subsequently advance without movement of such operating lever.

In testimony whereof I have signed this specification in the presence of two subscribing witnesses.

WILLIAM H. COLLIER.
